TELEVISION TUBE

Lothar Frenkel, Beaverton, Oreg., assignor to Allen B. Du Mont Laboratories, Inc., Clifton, N. J., a corporation of Delaware

Application April 19, 1957, Serial No. 653,854

1 Claim. (Cl. 313—25)

This invention relates to a television tube, and more particularly to a flat display device.

Prior art cathode ray tubes required that the tube be approximately as long as a diagonal of its faceplate. As larger pictures become desirable, they were obtained by making the tube longer. Pictures having a diagonal larger than 30 inches required a tube so long that it became impractical.

At this point it was realized that a new approach was necessary. The new approach, designated as a "flat display device," envisioned a structure similar to a mirror which could be hung on the wall, and whose thickness would be no more than five or six inches. In order to produce this result utilizing present television standards and transmitting techniques, this flat display device required about five hundred horizontal lines which could be energized sequentially, and about six hundred vertical lines which could be sequentially excited.

Two methods of excitation were suggested. The first required that signals be applied to selected lines, the operation of accomplishing this excitation being called "commutating". The second method required that electron beams be turned on or off to traverse a sequential series of given paths, this operation being known as "gating." As may be realized, commutation and gating were the most vexing problems associated with the production of a flat display device.

It is therefore the principal object of my invention to provide an improved display device.

It is another object of my invention to provide a display device which inherently obviates the need for commutation or gating.

The attainment of these objects and others will be realized from the following specification, taken in conjunction with the single figure of the drawing, which is a cross-sectional representation of my improved flat display device.

My invention contemplates a novel structured cathode ray tube wherein the position of the faceplate approaches parallelism with the axis established by the neck of the tube. Scanning is produced by well known means, and an inclined mesh, to which a potential is applied, causes the electrons to follow a curved path which strikes the fluorescent screen at a substantially perpendicular angle.

Referring now to the drawing, it will be seen that my device comprises an evacuated envelope 10 having a neck portion 12, an inclined mesh 14, and a faceplate 15 which approaches parallelism with said neck portion. A fluorescent screen 16 is deposited on the inner surface of said faceplate. The embodiment depicted illustrates a flared portion 18, and a backplate 20. As will be hereinafter shown, these latter sections may assume other configurations.

The inner surface of fluorescent screen 16 has deposited thereon a layer 22 of conductive material, these materials and their processing being well known in the art. Backplate 20, part of the sides of the envelope, and portions

of the inside surface of flared portion 18, are all coated with a conductive material 24 such as "Aquadag."

An electron gun 26 is placed in neck portion 12 in a manner known to those in the art, and produces an electron beam 28 which may be deflected in orthogonal directions by a yoke 30 and deflection plates 32. Other deflection means may of course be utilized. In the illustration yoke 30 will cause electron beam 28 to sweep back and forth into and out of the plane of the paper, while deflection plates 32 will cause beam 28 to move to the left and right.

If there is no signal applied to deflection plates 32 but deflection yoke 30 is now energized, it will be seen that the electron beam scan occurs in a plane, which 15 for reasons which will hereinafter become apparent, will be designated as the "horizontal scanning plane."

A high transmission mesh 14, one in which the area of the holes is large as compared with the area of the wires, is positioned within envelope 10 so that it forms an acute 20 dihedral angle with the previously described horizontal scanning plane. Since this angle between this plane and the mesh, as seen in the drawing, is measured from the axis of the tube as projected from neck portion 12, the dihedral angle will be described as "longitudinal." As 25 this plane mesh longitudinal dihedral angle becomes larger than a few degrees, the mesh approaches a position where it intercepts the electron beam. A source of potential maintains coating 24 and mesh 14 at the same potentials. Thus, once the electrons of beam 28 have left the influence 30 of the deflection system 30—32, they are in a free field, and therefore travel in a straight line.

Faceplate 15 of the tube is not positioned perpendicularly to the tube axis as in prior art tubes, but in a position which approaches parallelism with the axis. It is 35 this feature which permits my invention to provide a large display surface. A potential higher than that of coating 24 is applied to conductive film 22 on the faceplate.

When the electrons of beam 28 pass through the openings of mesh 14, they enter an electrostatic field which 40 exists between mesh 14 and conductive film 22. Under the influence of this field the path of the electrons is curved so that they approach fluorescent screen 16 in a substantially perpendicular direction.

Thus the energization of horizontal deflection means 45 30 causes the beam to scan in a horizontal scanning plane; as the electrons pass through the mesh openings they are attracted to the fluorescent screen; their sequential positions thereon therefore trace a straight line which will be horizontal.

50 It will be apparent that theoretically faceplate 16 is preferably parallel to the tube axis, that is, it forms with mesh 14 a longitudinal dihedral angle which is acute. The value of this angle is of course related to the plane mesh angle, and to practical tube considerations.

55 If now deflection plates 32 deflect beam 28 to the right to position 28' indicated by the dashed line, and this condition is maintained during another horizontal scan of deflection means 30, another horizontal line just above the previous one will be produced by the fluorescent material. Thus a series of horizontal and vertical scanning signals such as are used in the usual television system will produce a raster of parallel lines.

It will be realized that the raster will tend to have the 60 shape of an inverted keystone, but this can be corrected by progressively reducing the amplitude of the sweep produced by deflection means 30 as the beam approaches the bottom of the raster. It will also be realized that the upper horizontal lines will be progressively closer spaced, producing a vertical non-linearity in which the top of the presentation is compressed. This condition may be 65 corrected by progressively decreasing the signal applied to deflection plates 32 as the beam approaches the bottom

of the raster. Either or both of these distortions may be corrected by a compensating, or counteracting, electrode or electrodes placed within envelope 10 and adjacent to backplate 20. If a single electrode is used, its potential and outline would be such as to prevent successive electron paths from diverging as widely as they ordinarily would. If a plurality of compensating electrodes were desired, their relative potentials would accomplish the same result. However, since additional electrodes complicate the structure, the preferred solution would involve control of the sweep signals.

It will be realized from the drawing that the length of the electron beam path is longer when the beam is impinging on a lower corner of the presentation than when it strikes the upper center portion. It would therefore be desirable to modify the focusing potentials so that the focal strength varies with beam position. This situation is similar to the need for "converging potentials" in a three gun color television tube, and circuits for achieving the desired result are well known in the art.

While the illustration shows neck portion 12 as being approximately centered, it will be realized that the back surface of the neck could be aligned with backplate 20.

It will be obvious to those in the art that modulating the electron beam by any of the well known methods will produce a television picture.

While the above description has been presented in terms of monochromatic light, it is obvious that the various lines of light may be produced in color by proper deposition of phosphors which emit red, blue or green light.

Having described the principles of my invention and one embodiment thereof, I desire to be limited not by the foregoing specification and illustrations but only by the claim granted to me.

What is claimed is:

A display device comprising an envelope comprising a neck portion having electron beam producing means positioned therein; means establishing a horizontal scanning plane; a mesh positioned to form an acute longitudinal dihedral angle with said plane whereby said mesh intercepts said beam; means producing a free field between said mesh and said beam producing means whereby electrons in said free field tend to move in straight lines until they strike said mesh; a faceplate positioned to form an acute longitudinal dihedral angle with said mesh, said faceplate being on the side of said mesh which is remote from said beam producing means; means to produce an electron accelerating field between said mesh and said faceplate whereby electrons are directed toward said faceplate; means causing said beam to sweep a horizontal line on said mesh and on said faceplate; and vertical deflecting means to cause said beam to change the vertical position of said horizontal line.
